(57) **CLAIM**

I claim the ornamental design for a closure, as shown and described.

DESCRIPTION

FIG. 1 is a top perspective view of the claimed design; FIG. 2 is a bottom perspective view of the claimed design of FIG. 1;

FIG. 3 is a top view of the claimed design of FIG. 1; FIG. 4 is a bottom view of the claimed design of FIG. 1; FIG. 5 is a side view of the claimed design of FIG. 1; FIG. 6 is a top perspective view of another embodiment of the claimed design;

FIG. 7 is a bottom perspective view of the claimed design of FIG. 6;

FIG. 8 is a top view of the claimed design of FIG. 6; FIG. 9 is a bottom view of the claimed design of FIG. 6;

FIG. 10 is a side view of the claimed design of FIG. 6; FIG. 11 is a top perspective view of another embodiment of the claimed design;

FIG. 12 is a bottom perspective view of the claimed design of FIG. 11;

FIG. 13 is a top view of the claimed design of FIG. 11; FIG. 14 is a bottom view of the claimed design of FIG. 11; and,

FIG. 15 is a side view of the claimed design of FIG. 11.

1 Claim, 15 Drawing Sheets
